IMITATION GRASS MAT

George J. Kaderbeck, Hamburg, N. Y., assignor,
by direct and mesne assignments, of one-half
to Hamburg Floral Mfg. Co., Inc., Hamburg,
N. Y., a corporation of New York, and one-half
to The Joseph M. Stern Company, Cleveland,
Ohio, a corporation of Ohio

Application September 19, 1933, Serial No. 690,119

22 Claims. (Cl. 112—9)

My invention relates to imitation grass mats of the type now in common use for decorative purposes, such as used at indoor flower shows; for displaying outdoor furniture; for covering 5 mounds of soil dug from graves; for concealing the soil in graves, and for various other purposes.

Imitation grass mats of this kind are commonly made of raffia and various methods are 10 employed to arrange the raffia on and sew it or otherwise apply it to a suitable flexible foundation, such as burlap, with a view of having the raffia stand upright from the burlap or other foundation and simulate natural grass.

15 Raffia commonly used for this purpose is commercially sold in hanks or skeins, the strands of raffia being tied together at one end of the hank or skein and being twisted for convenience in handling and shipping and also with a view of 20 maintaining the strands in untangled condition. However, by reason of the twist given these strands of raffia it is necessary to straighten them so as to eliminate the twist, since it is highly desirable that these strands be substantially 25 straight in order that they may be arranged in regular order and severed in desired lengths, the severed short lengths being sewed or otherwise fastened to the burlap or other flexible foundation midway between their ends and shaken or 30 otherwise treated so that the portions at opposite sides of the stitching are directed upwardly away from the burlap or other foundation so as to simulate blades of grass rising from the soil.

Since raffia has a dull gray appearance in its 35 commercial state, it is dyed by giving it a shade of green in any approved manner, approaching that of grass, and it is also necessary, under present methods of manufacture, to dye the burlap or other flexible foundation a similar color or shade, especially since, after considerable usage, 40 the moisture in the raffia, provided by dyeing the same, evaporates and when used exteriorly this evaporation is considerably augmented by air and the sun, with the result that the short lengths 45 of raffia at opposite sides of the line of stitching curl upwardly more than intended or desired and expose portions of the burlap or other flexible foundation to which it is applied. In this condition the mat loses its attractiveness, and no longer 50 is a simulation of natural grass provided.

Imitation grass mats as now constructed, even when new, expose the burlap or other flexible foundation when laying the same on an uneven, and especially convex, surface, such as a mound 55 of soil adjacent a grave, this exposure being

caused by the separation of the rows of short lengths of raffia sewed to the foundation.

It is the object of my invention to provide an imitation grass mat which will not expose the burlap or other foundation of the mat when the 5 rows of short lengths of raffia stitched to the burlap or other flexible foundation curl up due to the raffia having become dry, or when the mat is used to walk upon and the rows of short lengths 10 of raffia become worn.

Another object of my invention is to provide an imitation grass mat which will have added 15 length of life, even though the regularly applied rows of short lengths of raffia curl up, or become worn away by reason of using it as a mat to be walked upon.

A further object of my invention is the utilization 20 of waste raffia, such as caused by the combing or shredding of the hanks or skeins of raffia with a view of straightening out the strands; such combing or shredding resulting in separating or loosening various lengths of raffia, which have heretofore been considered unusable.

Under my improved method I employ such 25 waste for an under or sub-layer, the ends of the various lengths or strands so used curling up where space is allowed and filling the voids between the regular rows of raffia used as the surfacing or exposed layer.

With the above and other objects to appear 30 hereinafter my invention consists in providing the burlap or other flexible foundation with a sub-layer of raffia, preferably so as to completely cover the foundation, and in applying short lengths of raffia to the so covered foundation.

My invention further consists in the novel 35 method of manufacturing imitation grass mats to be hereinafter described and pointed out in the appended claims.

In the drawings:

Fig. 1 is a perspective view of the burlap or other flexible foundation of a mat, showing the same provided with a covering in the form of a sub-layer of raffia, the sub-layer being removed 45 at one corner to disclose the burlap or other flexible foundation.

Fig. 2 is a perspective view of a retainer for 50 retaining short lengths of raffia in regular order, preparatory to sewing the same to the raffia-covered burlap.

Fig. 3 is a perspective view of a mat in the course of construction, showing the foundation 55 provided with the sub-layer of raffia, one row of short lengths of raffia sewed or otherwise applied thereto, and another row of short lengths of

raffia arranged to be sewed or otherwise applied by means of the retainer shown in Fig. 2.

Fig. 4 is a detached perspective view of a complete mat.

5 Fig. 5 is a longitudinal section taken through the mat along the center of one row of short lengths of raffia as applied thereto.

Fig. 6 is a cross section taken on line 6—6, Fig. 5.

10 When raffia is combed or shredded so that it assumes a more or less straight-lined condition, it is clamped between retainers, such as shown in the drawings, or otherwise, and cut to desired short lengths so that portions project evenly 15 from opposite sides of the retainers. With suitable waste at hand and a piece of burlap or other flexible material of the desired size, all material to construct the mat according to my invention will be at hand.

20 In the drawings the reference numeral 7 designates the burlap or other material used as a flexible foundation for the mat. 8 designates the waste raffia, which is in such condition that some strands are twisted, others curled, and still others 25 more or less straight-lined, and this waste raffia is placed in roughly assembled form over the burlap or other flexible foundation by spreading it evenly without any attempt to lay or press the end portions of the numerous strands of raffia 30 down against the flexible foundation, such end portions being permitted to retain their natural condition, with the result that many of these ends stand upwardly and project away from the flexible foundation, which is a desirable feature of 35 my invention, although not absolutely necessary. The waste raffia thus applied is basted by long stitches or otherwise to the flexible foundation, as indicated by the numeral 9 in Figs. 1 and 3. This waste raffia thus forms a sub-layer which 40 fully conceals the burlap or other flexible foundation, and has most of the end portions of its strands free, and many projecting upwardly where unbasted. This sub-layer therefore has a more or less grassy appearance, although not 45 one simulating a mowed lawn.

45 The numeral 10 designates a retainer in which the straight-lined raffia is clamped by placing it transversely to the length of the retainer and in a layer of the desired thickness. The raffia is 50 then cut along opposite sides of the retainer to provide short parallel lengths, as shown at 11, and in this form each retainer, with the raffia clasped therein, is placed upon the sub-layer of raffia basted to the foundation and sewed by running the needle of a sewing machine through the slot 55 12 in the retainer. The substantially straight-lined short lengths of raffia are therefore sewed to the raffia-covered foundation, as indicated at 60 13, Figs. 5 and 6, after which the upper member 65 14 of the retainer is removed from the lower member 15 thereof and the lower member slid laterally from underneath the applied row of raffia. The raffia, when released from the retainer, curls upwardly, as indicated along the upper edge in Fig. 3, or as indicated over the entire surface of 70 the mat shown in Fig. 4; and it is then roughened with the hands, or otherwise agitated or ruffled to aid in directing the ends of the short lengths of raffia upwardly to simulate the blades of grass 75 of a mowed lawn.

75 As clearly shown in Figs. 3, 5 and 6, the strands of raffia which provide the grassy-like surface for the mat, are preferably disposed at right angles to the direction of the waste raffia forming the sub-layer.

As clearly shown in Fig. 6 the rows of short length raffia are curved or directed upwardly and provide spaces between the rows along their lower regions directly above the sub-layer of raffia. The ends of the short strands of raffia of adjoining 5 rows lie in contact with each other and intermingle somewhat along their marginal portions so that when the mat lies flat, the ends of the short lengths of strands, may be referred to as the surface layer of raffia, appear to rise in 10 straight lines from the foundation and thus simulate the blades of grass rising in straight lines from the soil.

It is to be noted that many of the ends of the strands of waste raffia forming the sub-layer 15 project upwardly into the spaces between the rows of raffia forming the surface layer, as indicated at 16, Fig. 6; some of these ends rising to a height even with that of the raffia of the surface layer while others extend upwardly various distances.

When the surface layer becomes worn, or when the raffia becomes dry after a long period of use and curls up so that the adjacent rows are reduced in width and spaces provided along the 25 upper surface of the mat between the rows of raffia, the raffia forming the sub-layer will be exposed.

The mat will retain its grassy appearance even though the raffia of the surface layer becomes 30 completely dried, and in this connection it may be stated that when dyeing the mat, a chemical or other substance is employed which tends to keep the raffia moist and attract moisture to the raffia so that it will retain a fresh grassy appearance 35 for a considerable length of time. However, exposure to the sun or to dry air, will eventually result in completely drying the raffia of the upper layer and cause it to curl so that the rows of raffia forming the surface layer become separated. Even under such conditions, no portion of the coarse woven burlap will be exposed, since the raffia forming the sub-layer fully covers the same, and especially since the upstanding free ends of the strands of said sub-layer effectively fill the 40 gaps between the rows so formed, even though along regions thereof a lower level for the mat will be provided than that provided by the raffia forming the surface layer. A pleasing effect is retained for the mat, especially since the sub-layer will not have become dried out to the extent of the surface layer. This will assure a grassy 45 appearance over the entire surface of the mat for a considerable length of time, thus providing a useful life for the mat doubling that of a mat formed in the ordinary manner.

Having described the construction of my improved mat in conjunction with the method of making the same, I do not consider it necessary to separately describe the method of constructing the mat, but wish to state that the retainers and the method of applying and securing the rows of raffia forming the surface layer of the mat are merely representative, and that such surface layer may be otherwise applied; and, furthermore, that it is not essential that the waste raffia be arranged with its numerous strands in more or less parallel relation since, broadly considered, the use of a sub-layer of raffia, whether formed of waste material or otherwise, falls fully within 70 the scope of my invention as defined in the appended claims, regardless of its mode of application to the foundation; it being the purpose of my invention to cover those portions of the burlap or flexible foundation which would be exposed 75

when the rows of raffia forming the surface layer become separated, whether due to the wearing of such surface layer, to the drying of the raffia, or the placing of the mat upon a convex or similar surface in which the foundation of the mat would be flexed and the rows of raffia forming the surface layer separated to expose portions beneath. Moreover, it is not my intention to limit myself to the use of raffia, and when in the claims this term is employed, it is intended to include any fibrous or other strand-like material capable of use in the manner herein described.

I prefer to construct the mat completely while the several parts including the same are in their natural color and condition, and then dye the same to the desired color or shade, preferably green to simulate a mowed lawn.

By the term "layer", as used in the claims, I mean covering material formed of numerous strands or fibres formed in rows or assembled and spread out over the entire area or definite areas of the foundation, or backing as it may be termed; the covering material consisting preferably of strands or fibres of raffia in superimposed layers applied to a suitable foundation or backing, with one layer arranged over the other in any suitable manner so long as the numerous strands or fibres forming the lower or sub-layer are retained in place on the foundation or backing after applying the numerous short strands forming the upper or surface layer in regular rows; and it is to be understood that the relative disposition and regularity of the two layers of strands or fibres is immaterial so long as strands or fibres of the lower or sub-layer become exposed when the strands or fibres of the upper or surface layer separate at or along any region of the mat.

Having thus described my invention, what I claim is:

1. An imitation grass mat, comprising a flexible foundation, a layer of imitation grass material on said foundation to substantially cover the same, said imitation grass material having upwardly-directed free end portions, and a second layer of like material applied over said first layer and formed of rows of short lengths of material arranged to have the end portions of each row extending upwardly to simulate blades of grass and to have the end portions of adjoining rows in contact with each other to normally expose only the material of said second layer.

2. An imitation grass mat, comprising a flexible foundation, various lengths of imitation grass material laid substantially flat upon said foundation, and short parallel strands of imitation grass material arranged in rows and fastened between the ends of said short strands to provide upwardly extending end portions for said short strands simulating blades of grass, the material of adjoining rows being in contact to conceal the substantially flat imitation grass material beneath until from any cause the material in one of said rows of short parallel strands is separated from the material of an adjoining row.

3. An imitation grass mat, comprising a flexible foundation, a layer of waste imitation grass material on said foundation and secured thereto, said material having free end portions projecting upwardly from said foundation in irregular order, and a second layer of grass material arranged over the first-mentioned layer in regular order to simulate blades of grass and form a surfacing layer which under normal conditions substantially conceals the first-mentioned layer of imitation grass material, said first-mentioned layer

being exposed only when the material of said surfacing layer separates at or along any region.

4. An imitation grass mat, comprising a flexible foundation, a layer of imitation grass material applied to said foundation and fastened thereto, and a surfacing layer of imitation grass material applied to said first-mentioned layer and comprising rows of short lengths of grass material grouped in regular order transversely with respect to the trend of said rows and stitched in place lengthwise of said rows between the ends of said short lengths of material to form opposite free end portions for each row which are directed upwardly to simulate blades of grass, the material of adjoining rows lying in contact and when separating at any region exposing the material in said first-mentioned layer.

5. An imitation grass mat, comprising a flat foundation, a surface layer of imitation grass material formed of parallel rows of regularly grouped short lengths disposed transversely to the trend of said rows and fastened between the ends of said short lengths to form opposite end portions directed upwardly to simulate blades of grass, and like imitation grass material on said foundation beneath said surface layer so as to cover the same along regions between said rows and be exposed when the material of adjoining rows of said surface layer becomes separated.

6. An imitation grass mat, comprising a flexible foundation, a layer of waste raffia disposed over said foundation to substantially cover the same and to allow free ends of strands of raffia to assume any natural free condition, and parallel rows of short lengths of raffia grouped together in parallel order over said layer of waste raffia transversely to the trend of the rows of raffia and sewed approximately midway between the ends of said short lengths to the raffia-covered foundation so as to provide free portions for the short lengths of raffia of each row and permit said free portions to extend upwardly and simulate blades of grass, said upwardly extending free end portions providing spaces beneath the surface of the mat and between adjoining rows thereof into which free end portions of the first-mentioned layer of raffia extend.

7. An imitation grass mat, comprising a flexible foundation, a layer of raffia of various lengths on said foundation arranged to allow end portions of said various lengths to assume various positions in free condition, a surface layer of raffia applied over the so raffia-covered foundation formed of parallel rows of short lengths of raffia regularly grouped with the short lengths trending at right angles to the trend of said parallel rows, said rows being sewed to the said foundation between the ends of said short lengths of raffia to provide free end portions curved upwardly to simulate blades of grass and to provide spaces between the rows in regions below the upper surfaces thereof into which free ends of the first-mentioned layer of raffia extend, said last-mentioned raffia being exposed when end portions of said short lengths of raffia forming said parallel rows become worn, or when said short lengths of raffia become sufficiently dry to curl inwardly toward the plane of stitching of said parallel rows to said foundation.

8. The method of constructing imitation grass mats, which consists in applying substantially flat imitation grass material to one side of a flat foundation so as to substantially cover said foundation and in fastening over the so covered foundation short lengths of raffia having end portions

extending upwardly from said side of the foundation to simulate blades of grass.

9. The method of constructing imitation grass mats, which consists in applying various lengths of raffia to one side of a flexible foundation by fastening the raffia thereto, and in then sewing short lengths of raffia over the so covered foundation to provide opposite end portions for said short lengths directed in an upward manner to simulate blades of grass.

10. The method of constructing imitation grass mats, which consists in distributing raffia over the entire surface of a flexible foundation and fastening the raffia thereto so that end portions of the strands of raffia are free and may project upwardly from said flexible foundation, in then sewing rows of short parallel lengths of raffia uniformly grouped over the so covered foundation to provide upstanding end portions simulating blades of grass with raffia of each row lying in contact with raffia of an adjoining row to expose only the raffia of the various rows.

11. The method of constructing imitation grass mats, which consists in applying a layer of raffia to the upper surface of a flexible foundation, in then sewing over said layer of raffia a second layer composed of parallel rows of short lengths of raffia grouped in parallel arrangement to provide free upwardly-directed portions at opposite sides of the stitching with raffia of adjoining rows in contact and with end portions of the raffia first applied to said foundation extending irregularly upwardly into spaces between said parallel rows, and in then dyeing the mat so completed to desired shade or color, whereby a mat is provided in which the foundation is concealed when the short lengths of raffia separate between rows.

12. The method of constructing imitation grass mats, which consists in applying a layer of raffia to a flexible foundation, in clamping uniform short lengths of raffia in substantially parallel arrangement within retainers, in applying the retainers with the so clamped short lengths of raffia onto said layer of raffia, and in sewing the said short lengths of raffia to the foundation over said layer of raffia and removing said retainers from the short lengths of raffia so as to provide free upwardly-directed portions for the raffia at opposite sides of the stitching, with end portions of raffia of adjoining rows in contact and with end portions of the layer of raffia first applied to said foundation extending irregularly upwardly into spaces between said rows of raffia.

13. The method of constructing imitation grass mats, which consists in applying raffia to a flexible foundation, in clamping short uniform lengths of raffia in substantially parallel arrangement within retainers, in successively applying the retainers with the so clamped short lengths of raffia onto the so covered foundation, and in then sewing the said short lengths of raffia to the so covered foundation and removing said retainers from the short lengths of raffia so as to provide free upwardly-directed portions for the raffia at opposite sides of the stitching with raffia of adjoining rows in contact at the free upper ends so that the raffia first applied to said foundation becomes exposed when the raffia of adjoining rows separate.

14. An imitation grass mat, comprising a foundation, a layer of imitation grass material on one side of said foundation having free end portions, and a surfacing layer of imitation grass material over and fastened to said first-men-

tioned layer to simulate a layer of grass normally concealing said first-mentioned layer, said first-mentioned layer having free end portions extending upwardly between the imitation grass material of said surfacing layer and becoming exposed at any point of said mat at which the grass material of the surfacing layer separates.

15. An imitation grass mat, comprising a flexible foundation, a layer of imitation grass material on said foundation, and a surfacing layer of imitation grass material arranged over said first-mentioned layer and comprising rows of short lengths of grass material grouped in regular order transversely with respect to the trend of said rows and stitched in place lengthwise of said rows between the ends of said short lengths of material to form free opposite end portions for each row which are directed upwardly to simulate blades of grass, the material of adjoining rows lying in contact and when separating at any region exposing the material in said first-mentioned layer.

16. An imitation grass mat, comprising a flexible foundation, a layer of waste imitation grass material placed on one side of said foundation and having short free end portions projecting upwardly from said foundation, and a second layer of imitation grass material applied to said first-mentioned layer so as to extend upwardly from said foundation and simulate blades of grass, said second layer forming a surfacing layer which substantially conceals said first-mentioned layer of imitation grass material and said first-mentioned layer having free end portions extending upwardly into said second layer and being exposed only when said surfacing material separates at or along any region.

17. An imitation grass mat, comprising a flexible foundation, a substantially flat layer of imitation grass material on one side of said foundation, and a surfacing layer of imitation grass material applied to said first-mentioned layer and comprising rows of short lengths of grass material grouped in regular order transversely with respect to the trend of said rows and stitched in place to form upwardly-directed portions simulating blades of grass, the short lengths of grass material of adjoining rows lying in contact and when separating at any region exposing said first-mentioned layer of grass material, said first-mentioned material concealing said foundation at such region of separation.

18. An imitation grass mat, comprising a flexible foundation, imitation grass material in strand or fibre form and of irregular lengths laid substantially flat upon said foundation, and rows of short lengths of imitation grass material stitched to said foundation between the ends of said short lengths and normally concealing said irregular lengths of strands or fibres, said irregular lengths of strands or fibres being exposed to the eye only when said parallel rows of short lengths of imitation grass material or any portion of adjacent rows become separated.

19. An imitation grass mat, comprising a flexible foundation, and imitation grass material on one side thereof comprising two superimposed layers of assembled strands of grass material, the strands of each having upwardly-directed free end portions, said layers being so arranged that when the upper layer separates at any point the lower layer becomes exposed.

20. An imitation grass mat, comprising a flexible foundation, and two superimposed layers of

- assembled strands of imitation grass material on one side of said foundation substantially covering the same, each of said layers having upwardly-extending free end portions and one of said layers only being exposed when said flexible foundation is in flat condition and the other when said last-mentioned layer separates upon flexing of said foundation or when worn away at any surface region or regions.
- 10 21. An imitation grass mat, comprising a flexible foundation, and two superimposed layers of imitation grass material on said foundation, the grass material of each of said layers having upwardly-directed free end portions, the upper of said layers only being exposed and concealing the
- 15

lower and said lower becoming exposed only along regions when the upper layer is separated due to wear, exposure, or upon flexing of the mat.

22. An imitation grass mat, comprising a flexible foundation and imitation grass material composed of two superimposed layers of assembled strands of such material, the strands of each layer having free ended upstanding portions simulating blades of grass and one of said layers normally concealing the fibers of the other layer, 5 and when separated at any point or region exposing said other layer to conceal said foundation at the separated point or region.

GEORGE J. KADERBECK. 15
